UNITED STATES PATENT OFFICE

2,616,140

BUCKLE

Michael Rishcoff, Wilkes-Barre, Pa.

Application June 13, 1949, Serial No. 98,779

1 Claim. (Cl. 24—191)

1

This invention relates to an improved buckle. An object of this invention is to retain the fixed end of a belt in a slot formed in the outer or front plate of the buckle construction and to retain the opposite or free end of the belt in locked engagement with the under surface of the front plate through the expedient of an improved holder which includes a number of lugs fixed thereto which pass at least partially through and into a series or number of apertures formed in the front plate.

Another object of this invention is to mount the holder on the sides of the front plate by means of a pair of trunnions carried by the holder, to stop the pivotal movement of the holder by means of an extension or projection formed on the holder which engage the sides of the front plate or member and serve the purpose of providing a finger grip for operating the pivoted member with respect to the front plate member.

Ancillary objects and features will become apparent to those skilled in the art, in following the description of the preferred embodiments of the invention, illustrated in the accompanying drawings, wherein:

Figure 1 is a front view of the device;

Figure 2 is a back view of the device shown in Figure 1;

Figure 3 is an end view taken on the line 3—3 of Figure 1 and in the direction of the arrows;

Figure 4 is a top view of the device shown in Figure 2 as taken on the line 4—4 of Figure 2 and in the direction of the arrows;

Figure 5 is a transverse sectional view taken substantially on the line 5—5 of Figure 2 and in the direction of the arrows; and

Figure 6 is a perspective view illustrating a modification of a holder which is used in connection with the invention.

The buckle construction may be used in conjunction with substantially any type of belt and for substantially any purpose.

In each form of the invention, a generally similar front plate member is utilized. The front plate member includes a flat portion 8 which has right angularly disposed ends 10 and 12, respectively, extending therefrom. Openings (unnumbered) are provided in each end 10 and 12 and they are in substantial alignment.

A longitudinal opening 14 is provided in the front plate 8, leaving a belt loop retaining bar 16 extending longitudinally across the front plate. The loop of a belt is adapted to pass through the opening 14 so that it is fixed thereto.

2

A longitudinal row of openings or apertures, each of which is indicated at 18, is provided in the front plate 8. Smoothly curved guards in the form of louvers 20 are fixed to the front plate 8 and disposed partially over each aperture 18.

A holder, generally indicated at 22 is composed of substantially flat stock and has trunnions 23 projecting from opposite ends thereof. These trunnions are disposed in the apertures formed in the ends 10 and 12 of the plate so that the holder is pivotally carried by the plate.

Referring to Figure 5, the cross-sectional shape of the holder is evident. Since the holder consists of a substantially flat member 24 and is provided with a longitudinal row of holding pins or teeth 26 along one longitudinal marginal edge and a row of holding pins or teeth 28 provided on the opposite longitudinal marginal edge, a cut through the holding pins and the flat portion 24 illustrates a substantially U-shaped structure.

The holding pins 26 are adapted to pass through the openings or apertures 18 and they are of such length as to clear the guards 20 when the holder is rotated about the trunnions 23 as an axis. The holding pins 28 pass through the opening 14 but at the end thereof remote from the member 16.

One or more finger operators are fixed to the holder 22 and are inclined at an angle with respect to the plane of the flat part 24 thereof. Disposed at each end of the flat member 24 and along the same edge as the finger grip 30 is a pair of lugs 32 and 34 which engage a part of the front plate member to form a stop and which are used for finger receiving purposes to release the holder from the belt.

Referring to Figure 6, it is noted that a second holder, generally indicated at 40, is provided as a modification of the invention for use with the front plate member. The trunnions 42 and 44 extend from the central flat section 46 of the holder and are similar to the trunnions 23. The finger grip member 48 is identical to the finger grip member 30. The finger grip and stop members 50 and 52, respectively, along the same marginal edge as the finger grip 48 are identical to the stop and finger grip members 32 and 34. The differentiating feature is the use of sharply pointed holding pins 54 in lieu of the holding pins 26.

In each instance, any number of holding pins may be used as found desirable or necessary.

In operation, a belt is simply fastened to the front plate through the opening 14. The oppo-

site or free end of the belt is passed under the front plate 8 between the holder 22. Prior to the insertion of the free end of the belt, however, the holder 22 is rotated approximately 180° so that the holding pins 26 and 28 are in the opposite direction from that shown in Figure 5. Thereafter, the holder is rotated back so that the holding pins 26 pass through suitable openings in the belt while the holding pins 28 press the belt outwardly a slight amount through the opening 14, thereby causing the belt to assume a substantially S-shaped configuration.

Having described the invention, what is claimed as new is:

A buckle comprising an elongated, stationary front plate having an elongated opening in one of its longitudinal marginal portions defining an integral bar for connecting one end of a belt thereto and further having a series of spaced openings in its other longitudinal marginal portion, apertured flanges on the ends of said plate, an elongated rockable plate comprising trunnions on its ends journaled in the apertures of said flanges, belt engaging teeth on the longitudinal edges of the rockable plate engageable in the first and second named openings, outwardly

pressed louvers integral with the stationary plate immediately adjacent the second named openings and constituting guards for the adjacent teeth, means for manually actuating the rockable plate, and projections on the ends of said rockable plate engageable with the flanges for limiting the movement of said rockable plate in one direction.
